US0D1042540S

(12) **United States Design Patent** (10) **Patent No.:** **US D1,042,540 S**
(45) **Date of Patent:** **** Sep. 17, 2024**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Pablo Caro**, San Francisco, CA (US);
Woo-Ram Lee, Sunnyvale, CA (US);
Marcel van Os, Santa Cruz, CA (US);
Giancarlo Yerkes, Menlo Park, CA
(US)

(73) Assignee: **Apple Inc.**, Cupertino, CA (US)

(**) Term: **15 Years**

(21) Appl. No.: **29/877,309**

(22) Filed: **Jun. 5, 2023**

Related U.S. Application Data

(63) Continuation of application No. 29/813,776, filed on Nov. 1, 2021, now Pat. No. Des. 991,977, which is a continuation of application No. 29/753,933, filed on Oct. 5, 2020, now Pat. No. Des. 934,916, which is a continuation of application No. 29/684,917, filed on Mar. 25, 2019, now Pat. No. Des. 898,045, which is a continuation of application No. 29/617,041, filed on Sep. 11, 2017, now Pat. No. Des. 844,018, which is a continuation of application No. 29/563,715, filed on May 6, 2016, now Pat. No. Des. 797,122, which is a continuation of application No. 29/501,802, filed on Sep. 9, 2014, now Pat. No. Des. 755,839.

CLAIM

The ornamental design for a display screen or portion thereof with graphical user interface, as shown and described.

DESCRIPTION

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
